UNITED STATES PATENT OFFICE.

WILLIAM C. CLIFFORD, OF MANNFORD, OKLAHOMA.

HUMIDIFIER.

1,186,748.

Specification of Letters Patent. Patented June 13, 1916.

Application filed June 7, 1915. Serial No. 32,695.

To all whom it may concern:

Be it known that I, WILLIAM C. CLIFFORD, a citizen of the United States, residing at Mannford, in the county of Creek, State of Oklahoma, have invented certain new and useful Improvements in Humidifiers; and I do hereby declare the following to be a full, clear, and exact description of the invention, such as will enable others skilled in the art 10 to which it appertains to make and use the same.

This invention relates to certain novel and useful improvements in humidifiers.

An object of the invention is to provide a 15 humidifier which will blow moisture into a room and at the same time agitate the air.

A further object of the invention resides in supplying the device with water in such manner that the water carriers will be 20 constantly kept moist.

A still further object of the invention resides in providing novel means for conveying the surplus water from the carriers.

With these and other objects in view, such 25 as will appear as the description progresses, my invention comprises the combination and arrangement of parts as set forth in and falling within the scope of the appended claims.

30 Referring to the drawing: Figure 1 is a front elevation of my device. Fig. 2 is a vertical sectional view through the device taken in the plane of the fan. Fig. 3 is a side elevation of the device. Fig. 4 is a vertical sectional view taken at right angles to Fig. 2. Fig. 5 is a fragmental detail showing the manner in which the water is conveyed to the water chamber from one of the fan blades. Fig. 6 is a fragmental detail 35 showing the means for conveying the water to the water carriers.

Referring to the drawing wherein like parts are indicated by like characters throughout the several views: in the embodiment of my invention shown, I have illustrated a stand 1 on which is cast the usual motor casing 2 in which the motor is mounted in the usual manner. The particular construction of this motor and stand is not a 40 part of my invention inasmuch as any suitable motor and stand may be used and it is therefore thought unnecessary to illustrate this motor in detail. Secured to the shaft 3 of the motor is a fan 4 having a plurality 45 of blades 5. The end of each blade is bent back upon itself to form a chamber 6 having

end walls 7 therein. This end is extended slightly and forms a resilient bill 8 for clamping the water container in a manner to be described. Covering the face of each 60 blade 5 is a water container 9 formed of cloth or some other soft material that will readily absorb water. These water carriers 9 are secured to the inner ends of blades and extend into the chambers 6 in slight spaced 65 relation to the bottoms thereof and are secured therein by the bills 8. In order that these water carriers may be supplied, continuously, with water I have secured a reservoir 10 to the blades in alinement with the 70 shaft 3 which reservoir is rotatable with the fan and has a plurality of outwardly extending nozzles 11 each of which is in alinement with and lies over one of the blades. Extending into the reservoir 10 is a supply pipe 75 12 which is stationary and is loosely connected to the reservoir so that the reservoir may rotate with relation thereto. As the fan revolves the water is thrown outwardly 80 from the nozzles 11 by centrifugal force 85 and is absorbed by the carriers 9, the moisture is then blown into the air by the revolving of the fan.

During the operation of the device and because of the centrifugal feeding of the 85 water it will gradually work to the outer ends of the blades and in order that it may not be thrown off of these ends, I have provided the chambers 6 and in order that the water may be conveyed from these chambers 90 during the revolution of the fan I have provided a circumscribing chamber 13 in which is formed a continuous slot 14. Connected to one corner of each of the chambers 6 is an outlet pipe 15 which extends into the 95 slot 14. During the revolution of the fan the water is thrown by centrifugal force out of the pipes 15 into the chamber 13 through the slot 14 therein. The water is conveyed from the chamber 13 to an outlet pipe 16 100 having a suitable cock 17 therein.

In operation the reservoir 10 is supplied with water through the pipe 12 and the carriers 9 dampened at which time the continuous revolution of the fan will throw moisture into the air at the same time the air is agitated. The surplus water works gradually by centrifugal force to the ends of the blades of the fan and is caught in the chambers on the said ends, the water is then thrown from the chambers through the pipes connected thereto into the circum-

scribing chamber and finally conveyed therefrom.

Thus it will be seen that I have provided a humidifier by means of which the air will be kept moist but of such construction that there will be no possibility of the surplus water escaping therefrom.

While I have illustrated and described a particular embodiment of my invention, I have merely done so for the sake of convenience and I do not wish to be limited to that particular embodiment as it is obvious that numerous changes may be made within the details of construction thereof without 10 in any way departing from the spirit of the invention or exceeding the scope of the appended claims.

What I claim is:—

1. In a humidifier, the combination with 20 a fan, of an absorbent material secured to each blade thereof, means for supplying water to the inner end of each blade, means for accumulating the water at the outer ends of the blades, and means for receiving the 25 water from the said accumulating means.

2. In a humidifier, the combination with a fan having an absorbent material on the blades thereof, of a water reservoir secured concentrically with the axis of the fan, said 30 reservoir being constructed and arranged to eject water therefrom upon the rotation of the fan onto said absorbent material, cham-

bers at the ends of the blades of the fan for accumulating water therefrom, centrifugally controlled outlet pipes in said chambers, and 35 a circumscribing chamber for receiving the water from said outlet pipes.

3. In a humidifier, the combination with a fan having absorbent material on the blades thereof, of centrifugally controlled 40 water feeding means for supplying the absorbent material with water, means for collecting the water from the ends of the blades, and means for conveying the water from the said last mentioned means. 45

4. In a humidifier, the combination with a fan having a plurality of blades, of absorbent material secured to the blades, a water reservoir secured to the fan centrally thereof and having radiating pipes arranged 50 in alinement with the blades, chambers on the ends of the blades, a pipe connected to each chamber and extending outwardly therefrom, and a circumscribing chamber having a slot therein, the said pipes extending 55 into said slot throughout the entire revolution of the fan.

In testimony whereof, I affix my signature, in the presence of two witnesses.

WILLIAM C. CLIFFORD.
